ELECTRICAL RELAY

Joseph F. Ebert, Hollis, N. Y., assignor, by mesne assignments, to Allied Control Company, Inc., New York, N. Y., a corporation of New York

Application September 12, 1942, Serial No. 458,173

8 Claims. (Cl. 200—104)

This invention relates to electrical relays and more especially to small compact relays for use where there is likely to be heavy vibration or the like and this application is a continuation-in-part of applicant's co-pending application, Serial No. 415,167, filed October 16, 1941.

One of the objects of this invention is to provide a small compact relay of great strength and durability which will fit into the limited space available for it in airplane installations and will function efficiently and properly for a long time despite the severe vibrations to which it is subjected during operation of an airplane.

In the past, various types and constructions of relays have been proposed and used. Many of these are successful in their operation, but there are certain inherent disadvantages therein. In most cases, the arrangements of the parts are such that considerable difficulty and expense is necessary in the fabrication thereof. This renders such relays, in many instances, too expensive for certain uses. Some of such relays required various metal parts which had to be bent to complicated shapes before being assembled with the other elements of the relay. This required a number of additional operations which further increased the expense of the finished product.

The present invention is intended and adapted to overcome such disadvantages and to provide a relay structure in which there is incorporated a molded insulating member of such form, and cooperating with the other elements in such a manner, as to render the relay simple in construction and easy to assemble.

It is also among the objects of the present invention to provide a relay wherein certain of the metal parts, specifically, terminal elements, may be flat pieces of metal and these may be assembled without any bending operations.

It is still further among the objects of the invention to provide a structure wherein various elements constituting the relay may be readily assembled by screws and firmly held in place for functioning while at the same time allowing ready removal thereof for repair or replacement.

In practicing the present invention I provide a magnetic circuit consisting of an iron or similar member in the form of a U having a central flat face and legs extending therefrom at right angles to said face. One of the legs is provided with means for securing to a suitable support, and therefore constitutes the base of the relay, as well as part of the magnetic circuit.

The other leg is secured to an insulating member which is in the form of a plate having a

recess formed in one of the faces of such size and shape as to accommodate the leg of the U. On the other surface of the insulating plate are integrally formed a number of raised portions on which the various terminal elements may be secured and such elements, while in the form of flat plates, may be so positioned that they cooperate with each other and with contact arms, without the necessity of bending or fabricating such elements.

Each of the terminal elements is secured to the insulating plate by means of a single screw member. The said elements and the insulating plate are formed with cooperating projections and depressions whereby the entrance of a projection into a depression serves as an anchoring point for the terminal and the screw serves as means for firmly holding the terminal in place against accidental movement, while at the same time allowing removal of the terminal when desired.

By reason of such a structure there is required a minimum number of metal pieces and only a single piece, namely, the magnetic circuit, requires any bending operations. A number of parts in the relay have been materially reduced, and the assembly thereof is an extremely simple matter. At the same time, all of the terminals are readily accessible for the soldering of wires thereto for repair and for replacement. Because the insulating plate has been made in the form as stated above, there have been eliminated a considerable number of operations, thereby not only decreasing the cost of the relay, but increasing its strength, sturdiness, efficiency and life.

In the accompanying drawing constituting a part hereof and in which like reference characters indicate like parts:

40 Fig. 1 is a side view of a relay embodying the present invention, having some parts broken away for clearness;

45 Fig. 2 is an elevational view taken from the back of the relay, showing the outside of the face of the magnetic circuit;

Fig. 3 is a top plan view thereof showing the various metal members and their relation to each other;

50 Fig. 4 is a plan view of the insulating plate or member detached from the remainder of the relay;

Fig. 5 is an underneath view of the insulating plate to show the form thereof for reception of a leg of the U;

Fig. 6 is a front elevational view of the insulating plate;

Fig. 7 is a side elevational view thereof; and

Fig. 8 is a cross-sectional view taken along the line 8-8 of Fig. 3, showing the assembly of a terminal in the insulating plate.

There is provided a plate 1 having the ends 2 and 3 bent at right angles thereto, a screw 4 passing through said plate and holding coil 5 in position. Leg 3 of the U, so formed, constitutes a base to be secured to a suitable support. The sides 6 of plate 1 are tapered and leg 2 is of lesser area than leg 3. A molded insulating plate 7 has a rim 8 formed on one side defining a flat surface onto which leg 2 is fitted and secured. A pair of terminal clips 9 held in slots 10 are joined by wires 11 to coil 5.

Armature 12 is hinged at 13 to leg 2 and has its upper end 14 bent at right angles to partly overlie plate 7. Insulating block 15 is secured to end 14 and has two contact arms 16 mounted thereon. Wires 17 therefrom connect with clips 18. The extended ends 19 of arms 16 have terminal buttons 20 and 21 adapted to contact with corresponding buttons on the relay.

As shown more particularly in Figs. 2, 3 and 8, the insulating plate 7 has formed on its upper surface a pair of raised portions 22 providing a recess therebetween. A bolt 24 sets into the recess and carries spring 25. Fork 26 straddles the bolt below the spring, and is fixed to block 15, whereby the armature is biased away from the coil. Contact buttons 27 (Fig. 8) cooperating with buttons 20 and having projections 28 fitting into openings 29 in portions 22, are fixed on metal terminal plates 30. Openings 31 are provided to accommodate lead-in wires which are to be soldered or otherwise secured in place. At the opposite ends of plates 30 are openings 32 in alignment with metal inserts 33 for the reception of screws 34. This construction holds the plates 30 in position with a single screw and utilizes the head 28 of button 27 as an anchor for the terminal.

A pair of raised end portions 35 are located above and laterally of portions 22. Integral projections 36 are formed on the upper surfaces of portions 35. Terminal plates 37 are held by screws 38 passing through central openings and into threaded metal inserts 39 in portions 35. Openings 40 provide means for attaching lead-in wires and openings 41 are fitted over projections 36, whereby the terminals 37 are capable of being fixed in position by a single screw with no possibility of accidental movement of the terminals. Extensions 42 overlie the free ends 19 of contact arms 16 and have contact buttons 43 on the lower faces thereof to align and make contact with corresponding buttons 21 on said arms.

By reason of the present construction, the fabrication of the relay has been greatly simplified in various respects. Machining operations, cutting, trimming, fitting, and the like have been entirely eliminated with a great saving of time, labor, and materials. The use of the insulating plate with the various raised and depressed portions provides a single member which may be made in large quantities and at very low cost. Around this insulating member are assembled the several parts to complete the relay. The various terminal and contact elements are simple, flat plates readily punched from sheet metal at low cost, without the necessity of any finishing operations and without any bending operations,

since the insulating member is so constructed that such flat pieces can be located in proper cooperative positions. Such pieces are of simple shapes requiring only very simple dies.

After the assembly is made, the several electrical connections on the contacts and terminals are easily attached since all such members are on the top of the relay away from the base and its support, and the points of attachment are along the outer edges of the insulating members, giving great accessibility and convenience with ease of working. The terminals being held in place by screws at the top of the relay allow ready removal thereof for repair or replacement. The several factors involved result in a compact structure which is sturdy and which will withstand an extraordinary amount of strain, abuse and, particularly, severe vibration. Because of its compactness the present relay may be fitted into places where other relays of similar capacity could not be used. Only one metal piece requires a bending operation, namely, the magnetic circle, and this serves not only as a base but also as a support for the insulating plate, thus eliminating several parts.

Various changes in the mechanical arrangement of the parts, the materials used, the specific form of the elements, and the like may be made within the spirit of the invention, the scope of which is set forth in the claims appended hereto.

What I claim is:

1. In a relay, a magnetically conductive frame consisting of a cross member and two leg members extending from the ends thereof in the same direction and at right angles to said cross member with one leg member constituting a base for supporting said frame, a coil fixed to said cross member with its axis at right angles thereto and located between said leg members, a hinge formed at the end of said other leg member, an insulating plate secured to said other leg member, a contact member on said insulating plate, an armature fitted on said hinge and substantially parallel to said cross member, a contact arm carried by and insulated from said armature and overlying said insulating plate for co-operation with said contact member, and a spring biasing said armature away from said coil.

2. In a relay, a magnetically conductive frame consisting of a cross member and two leg members extending from the ends thereof in the same direction and at right angles to said cross member with one leg member constituting a base for supporting said frame, a coil fixed to said cross member with its axis at right angles thereto and located between said leg members, a hinge formed at the end of said other leg member, an insulating plate secured to said other leg member and having a pair of outwardly projecting portions, a contact member carried by each of said portions substantially in alignment with said cross member and spaced laterally of the center of said plate, an armature fitted on said hinge and substantially parallel to said cross member, a pair of contact arms carried by but insulated from said armature and overlying said insulating plate for co-operation with said contact members, and means biasing said armature away from said coil.

3. In a relay, a magnetically conductive frame consisting of a cross member and two leg members extending from the ends thereof in the same direction and at right angles to said cross member with one leg member constituting a base for supporting said frame, a coil fixed to said cross

member with its axis at right angles thereto and located between said leg members, a hinge formed at the end of said other leg member, an insulating plate secured to said other leg member and having a pair of outwardly projecting portions, a contact member carried by each of said portions substantially in alinement with said cross member and spaced laterally of the center of said plate, an armature fitted on said hinge and substantially parallel to said cross member, an angular extension on said armature overlying said insulating plate and having an insulating block on the upper face thereof, a pair of contact arms carried by said block and co-operating with said contact members, and a spring biasing said armature away from said coil.

4. In a relay, a magnetically conductive frame consisting of a cross member and two leg members extending from the ends thereof in the same direction and at right angles to said cross member with one leg member constituting a base for supporting said frame, a coil fixed to said cross member with its axis at right angles thereto and located between said leg members, a hinge formed at the end of said other leg member, an insulating plate secured to said other leg member and having a pair of outwardly projecting portions, a contact member carried by each of said portions substantially in alinement with said cross member and spaced laterally of the center of said plate, an armature fitted on said hinge and substantially parallel to said cross member, a pair of contact arms carried by but insulated from said armature and overlying said insulating plate for co-operation with said contact members, said extension having a slotted inner end, a stud secured to said insulating plate and being embraced by the slotted inner end of said extension, and a coil spring surrounding said stud and engaging said extension to bias said armature away from said coil.

5. In a relay, a magnetically conductive frame consisting of a center section and two leg sections extending from the ends thereof at right angles to said center section with one of said leg sections constituting a base for supporting said frame, a coil fixed at one end to said center section and located between said leg sections, a movably supported armature extending across the remaining end of said coil, an insulating plate attached to the remaining leg section, a stationary contact supported thereby, a contact arm carried by but insulated from said armature for movement into and out of engagement with said stationary contact, and means biasing said armature to effect movement of said contact arm relative to said stationary contact upon de-energization of said coil.

6. A relay comprising a magnetically conduc-

tive frame in the form of a U having a central face and legs at right angles thereto with one of said legs being adapted to constitute a base for the relay, a coil supported by said central face between and parallel to said legs, an armature hinged to the remaining leg and extending across the end of said coil, a block of insulating material having in one face a recess receiving said remaining leg and having an integrally formed raised portion on the opposite face, a contact arm insulatingly supported by said armature and extending at right angles therefrom, a contact member carried by said raised portion and lying in the path of said contact arm, and means biasing said contact arm and armature relative to said contact member.

7. A relay comprising a magnetically conductive frame in the form of a U having a central face and legs at right angles thereto with one of said legs being adapted to constitute a base for the relay, a coil supported by said central face between and parallel to said legs, an armature hinged to the remaining leg and extending across the end of said coil, a block of insulating material having one face contacting said remaining leg and having two different level integrally formed raised portions on the opposite face, a contact arm insulatingly supported by said armature and extending at right angles therefrom across the lower level portion, a contact member carried by said lower level portion in underlying relation to said contact arm, a contact member carried by said higher level portion in overlying relation to said contact arm, and means biasing said contact arm toward one contact member.

8. A relay comprising a magnetically conductive frame in the form of a U having a central face and legs at right angles thereto with one of said legs being adapted to constitute a base for the relay, a coil supported by said central face between and parallel to said legs, an armature hinged to the remaining leg and extending across the end of said coil, a block of insulating material having one face contacting said remaining leg and having two different level integrally formed raised portions on the opposite face, a contact member insulatingly supported by said armature and extending across the lower level portion, a contact member carried by said lower level portion in underlying relation to said contact arm, a contact member carried by said higher level portion in overlying relation to said contact arm, a stud supported by said block, an arm carried by said armature and having a recess receiving said stud, and a spring supported by said stud in engagement with said arm to bias the armature relative to said block.

JOSEPH F. EBERT.
